HEAT EXCHANGER

Hugh D. Heron, Outremont, Quebec, Canada

Application January 21, 1946; Serial No. 642,551

6 Claims. (Cl. 285—45).

1

This invention relates to improvements in the construction of heat exchangers such as vapour condensers, especially marine condensers, and relates more particularly to the connection of exchanger tubes to exchanger tube plates, being an improvement on my earlier invention disclosed in United States Patent No. 2,342,398, dated February 22, 1944.

For convenience, the invention will be described with relation to marine condensers but it will be understood the invention is not thereby limited to that application but extends to other types of heat exchangers.

The primary object of the invention is to provide, in combination with a construction in general according to my said earlier invention and with the retention of all the advantages thereof, means for holding the exchanger tubes against creeping through the packing thereof and through the tube plates and against oscillatory movement which tends to loosen the packing and cause leaking. A further object is to provide construction permitting free movement of tubes in expansion and contraction due to temperature changes, without damage to packing and with exclusion of grit, mud or scale from the clearance between the tubes and the tube holding means. A still-further object is to provide protection against drying out of the packing when an exchanger is temporarily out of service. Another object is to provide a construction which is easier and less expensive to produce and which may more easily and quickly assembled than the construction now in general use. Still another object is to provide construction applicable to existing exchangers having the usual internally threaded packing chambers, either to convert the same to embody the features of this and of my former invention or as an emergency substitute for the usual connection between tubes and tube plates. Various other objects and the advantages of the invention may be ascertained from the following description and the accompanying drawings.

The invention consists essentially in providing a heat exchanger having packing receiving recesses in the tube plates thereof formed to retain packing therein independently of any additional retaining means, in combination with means adapted to hold the exchanger tubes against creeping through the tube plates and packing; to exclude foreign matter from between the tubes and the holding means therefor and to protect the packing against the effects of tube vibration and against drying out when the exchanger is temporarily out of service.

In greater detail, the invention consists in the features and combinations of features herein disclosed, together with all such modifications thereof and substitutions of equivalents thereof as are within the scope of the appended claims.

2

In the accompanying drawings, forming part of this specification, which illustrate that form of the invention now preferred for new construction, and further illustrate modifications thereof for the adaption of the invention to existing condensers, but to the details of all of which the invention is not confined:

Fig. 1 is a fragmentary side elevation of a condenser.

Fig. 2 is an elevation of a fragment of a tube plate showing the ends of tubes and retaining means therefor.

Fig. 3 is a section on the line 3—3 of Fig. 2, showing the relations of the parts as now preferred for new construction.

Fig. 4 is a section similar to that of Fig. 3, showing modifications.

Figs. 5 and 6 are sections similar to that of Fig. 3, showing ways of adapting the invention to existing condensers.

Referring more particularly to the drawings, 11 designates condenser tube plates and 12 condenser tubes mounted in the plates. The tube plates are formed with apertures 13 therein for passage of the tubes, which apertures are usually located as close together as is possible consistent with adequate strength of the tube plate, so as to provide the maximum number of tubes within a given space. Each aperture 13 comprises three portions, namely, an inner portion 14, an intermediate portion 15 and an outer portion 16. The inner portion 14 is cylindrical and of such diameter that the tube is an easy sliding fit therein. The intermediate portion 15 is of larger diameter than the inner portion so as to provide an annular packing space around the tube, the shoulder 17 between the inner and the intermediate portions being preferably flat and normal to the aperture axis, but may be otherwise formed. The circumferential wall of the intermediate portion is tapered through at least a part of its depth, toward the outer end of the aperture so as to form a shoulder facing the shoulder 17, but may be cylindrical in its inner portion, as shown at 18 in Fig. 4. The circumferential wall of the outer aperture portion 16 is preferably cylindrical and preferably of slightly greater diameter than the outer end of the intermediate portion 15, so as to provide a narrow shoulder 19 at the junction of the intermediate and outer portions. Preferably the diameter of the outer portion 16 is approximately the same as the maximum diameter of the intermediate portion, as shown in Fig. 3, but may be of the same diameter as the outer end of the intermediate portion, as shown in Fig. 4, in which case there is no shoulder 19. The depth of the outer portion is materially greater than the longitudinal expansion of the tube 12, preferably three to five times the expansion.

The maximum diameters of the apertures 13

are preferably no greater than the maximum diameters of the usual internally threaded packing spaces, such as are shown in Figs. 5 and 6, so that it is possible to provide at least the usual number of tubes in a condenser of given size without weakening the tube plates by bringing the apertures any closer together than is usual.

In the outer portion 16 of each aperture there is provided a metal washer or ring 20 which preferably completely fills the aperture around the tube and which is an easy sliding fit on the aperture wall and on the tube, so that the tube may move freely through the ring when expanding or contracting. Normally the ring rests on the seat 19 and the outer end surface of the ring is flush with the outer surface of the tube plate 11. The bore of the ring is flared from the inner end surface of the ring, or from a line adjacent the inner end surface of the ring, as shown at 21, to within a short distance of the outer end surface and is parallel, or cylindrical, from the flare to the outer end surface of the ring, as shown at 22. The depth of the parallel portion 22 is at least as great as the longitudinal expansion of the tube when heated in service. The total angle of flare is preferably from 10° to 30°.

The packing now preferred is a single sleeve 23 of water swellable compressed fibre which, in its dry condition, is an easy sliding fit on the tube and into the small end of the intermediate aperture portion 15. The length of the packing sleeve is preferably only slightly less than the depth of the intermediate aperture portion.

The sleeve 23 is preferably composed of that type of material formed by winding a ribbon of paper or the like impregnated with a suitable binding agent, around a mandrel until a suitable wall thickness is built up and then compressing the tube in its radial direction. Sleeves of such material, when exposed to water, swell radially but do not swell appreciably in their axial direction.

If desired, instead of using a single sleeve, I may use a series of rings or washers 23^a of the same material, as shown in Fig. 4. This subdivision of the packing into rings facilitates penetration of moisture to all parts of the packing and thereby expedites swelling of the packing but has the disadvantage of longer assembly time.

The length of the tubes 12, when cold, is preferably less than the distance between remote faces of the tube plates 11 by about twice the longitudinal expansion of the tubes when heated to maximum working temperature, so that, when cold, the ends of the tubes are slightly below the outer surfaces of the tube plates, as shown. Thus, even if one end of a tube remains fixed, the longitudinal expansion resultant of heating to maximum working temperature will not cause the free end of the tube to project beyond the surface of the tube plate. In this way turbulence of fluid in the condenser is avoided.

After the tubes are in place in the tube plates and the packing and end rings have been inserted at both ends of the condenser in the manner shown, both ends of each tube are flared or radially expanded into surface contact with the flared bore portions 21 of the end rings 20. The radial expansion of the tube ends is only that sufficient to hold the tubes against creeping due to expansion and contraction, to inertia and to the urge of unidirectional flow through the tubes and does not normally place the tubes under tension between the tube plates at opposite ends

of the condenser. It is not the intention that flaring of the tube ends should so expand the same in the rings 20 as to interfere with free sliding of the tubes through the rings. It will be readily understood that, because of the outward flare of the ring bores, the tubes can be expanded, when cold, into substantially fluid tight contact with the flared surfaces of the rings without interfering with the free movement of the tubes through the rings as the tubes expand with heating.

When the tubes are radially expanded, the outer end edges thereof are in contact with the inner ends of the cylindrical bore portions 22 of the rings 20. As the tubes expand longitudinally with heating, the outer end edges thereof maintain contact with the cylindrical bores 22 of the rings and exclude mud, scale or the like from entering between the now spaced flared portions of the tubes and the flared bore surfaces 21 of the rings. Thus, no foreign matter can enter between the flared surfaces and set up tension in the tubes when they cool and contract.

When the condenser is assembled, there is a small annular clearance 24 around the inner end of each packing sleeve, which clearance tapers to nothing at the outer end of the sleeve, as clearly shown in Figs. 3 and 4. In service, moisture penetrates into the intermediate aperture portion 15 and causes the packing to swell radially and fill the spaces 24. Thereafter the expansive pressure of the packing is exerted between the tapered wall surfaces and the tubes, the effect of the tapered wall surfaces being to urge the packing inwardly against the shoulders 17. The packing is retained between the tapering walls of the recesses and the shoulders 17 and is not moved by the tubes as they expand and contract with changes of temperature. As there is little or no longitudinal expansion of the packing sleeves and as the tapered encircling walls urge the packing away from the rings 20, these do not normally function to retain packing but serve mainly to hold the tubes against creeping and against oscillation due to vibration. Vibration of the tubes when in service tends to produce oscillation of the tube ends, which oscillation, if unchecked, tends to wear or expand the packing and cause leaking between the packing and the tubes. The metal rings 20 restrain the tendency to oscillation and thereby protect the packing. Moreover, the rings seal the outer ends of the packing recesses and retard drying out of the packing when the condenser is temporarily out of service, so that there is little or none of the customary leaking when the condenser is again put into service.

For the conversion of an existing condenser having the usual internally threaded packing recesses, designated 25 in Figs. 5 and 6, whether the threads extend only part way to the inner ends of the recesses, as in Fig. 5, or extend to the inner ends, as in Fig. 6, the outer end of the packing recess may be reamed out to remove the threads to a sufficient depth to provide a receptacle for the ring 20. If the threads are not removed in the remainder of the recess to produce the structure of Fig. 3, the packing sleeve used, designated 26, is externally threaded to cooperate with the threads of the recess, which then form shoulders retaining the packing in lieu of the tapered wall of Fig. 3. A simple cylindrical packing, as shown in Figs. 3 and 4, is not satisfactory in connection with an internally threaded recess since, even though the packing will swell

sufficiently to effect a satisfactory retaining engagement with the threads of the recess wall, the packing does not swell sufficiently to completely fill the threads and therefore leaves a helical channel through which leaking can occur. An exception is found in the case of recesses in which the threads do not extend to the bottom of the recess. In such case, the packing sleeve will expand against the unthreaded wall portion with sealing effect, irrespective of whether the remainder of the sleeve is threaded or not.

Alternatively, to render the invention applicable without alteration to the tube plate, an externally threaded packing sleeve 26 may be inserted in the packing recess and followed by a tube retaining ring 20^a, similar to the ring 20 except that it is externally threaded to cooperate with the treads of the recess. The tube end is expanded in the ring 20^a, as already described for the ring 20.

The assembling of a condenser constructed according to this invention is extremely simple, quick and easy. When the tubes are in place, the packing sleeves and end rings are easily inserted and cannot be improperly inserted. The expansion of the tube ends is slight and is easily accomplished, as by a sharp blow on an expanding tool inserted in the tube end. The usual expenditure of time and labour in compressing packings by impact or by inserting and tightening packing nuts is entirely eliminated, together with the uncertainty of the result thereof.

It will be seen that in all cases the packing swells against the walls of the packing recesses with retaining effect independently of the end rings and that the tube is held against oscillation at its ends and against creeping by the end rings. The thickness of the rings is greater than the maximum elongation of the tubes so that even if an expanding tube should carry an end ring with it, the ring will not lose contact with the wall of its containing recess and will be drawn back into place when the tube contracts, thereby to serve as sealing means to retard drying out of the packing.

Claims directed to the packing member 26 and to the ring members 20 and 20^a are presented in a continuation-in-part application Serial No. 177,991, filed August 7, 1950.

Having thus described my invention, I claim:

1. In heat exchangers, including a pair of tube plates apertured for passage of tubes and tubes passing through said apertures; said apertures being in their outer portions of larger diameter than the tubes to provide packing recesses around the tubes and packing in said recesses; a single rigid metal end ring filling each of the recesses outside the packing, the bores of said end rings being flared and the tubes being expanded at each end into the flared bore portions of the rings, thereby to hold the tubes against creeping.

2. In heat exchangers and the like, tube plates apertured for passage of tubes; tubes passing through said apertures; the said apertures each having an inner portion of tube size and intermediate and outer portions of greater than tube size, the said intermediate portions having mutually facing shoulders; packing in said intermediate portions engageable with said shoulders to be thereby held against displacement in the longitudinal direction of the tubes; said outer aperture portions being of larger diameter than the intermediate portions; and metallic rings filling said outer aperture portions around the tubes.

3. Structure according to claim 1 in which the packing recesses are internally threaded and the packing and end rings are externally threaded to cooperate with said internal threading.

5. In heat exchanger construction including a tube plate apertured for passage of a tube and a tube passing through said aperture, the aperture being in its outer portion of larger diameter than the tube to provide a packing recess around the tube, and packing in said recess; a rigid metal ring filling the recess outside the packing, said ring having the bore thereof flared in an inner portion of its length and cylindrical in the outer portion of its length, and the tube end portion being expanded into the flared bore portion of the ring and having sliding contact with the cylindrical portion of the ring bore, thereby to prevent entrance of solid matter between the flared surfaces of the tube and ring when such surfaces are separated due to expansion of the tube.

5. In heat exchanger construction including a tube plate apertured for passage of a tube and a tube passing through said aperture, the aperture being in its larger portion of larger diameter than the tube to provide a packing space around the tube and packing in said space; a rigid metal ring filling the space outside the packing, said ring having an inner cylindrical bore portion in which the tube is a sliding fit, an intermediate portion flaring away from the tube and an outer cylindrical portion larger than the tube, the end portion of the tube being flared to conform to the flared portion of the ring bore and having sliding engagement with the outer cylindrical portion of the ring bore, thereby to prevent entrance of solid matter between the flared surfaces of the tube and ring when the same are separated by expansion of the tube.

40. 6. A packing for heat exchangers including tubes and tube plates having internally threaded recesses around tube ends providing packing receiving spaces, said packing comprising an externally threaded, compressed, water swellable fibre sleeve adapted to be screwed into a plate recess in close engagement with a tube and with the bottom and threaded wall of the recess; and an externally threaded, rigid, metal ring adapted to be screwed into the outer part of a plate recess 45 against said packing and to fill the space between the recess wall and the outer end portion of the tube, outwardly of the packing, the bore of said ring being at its outer end larger than the tube and tapering inwardly to tube size, whereby the tube may be expanded into said tapered bore portion to limit movement of the tube in its axial direction.
